PENNSYLVANIA.

DERAILER.

Application filed February 12, 1927. Serial No. 167,695.

This invention relates to derailers, more particularly to portable derailers which are adapted to cooperatively engage a rail for the purpose of derailing a vehicle crossing 5 thereover.

It is among the objects of this invention to provide a portable derailing device which shall be of simple, compact and durable mechanical construction, which shall embody 10 a minimum of parts, and which shall be relatively inexpensive to manufacture.

Another object of the invention is to provide a derailing device of the above designated character which shall be of relatively 15 light weight and which shall be adapted to cooperate with a rail and cross tie support to secure it in its operative position without the aid of any auxiliary clamping means.

Numerous forms of derailing devices have 20 been heretofore proposed which are adapted to cooperate with a rail and rail support in various manners, and some of these prior art devices are designed to be portable in the sense that they may be changed from 25 place to place on account of being detachably secured to the rail or cross ties, or both. All of the prior art devices requires some fastening means usually in the form of clamping members embodying screws or 30 jacks.

In accordance with the present invention it is proposed to provide a truly portable device in the sense that it can be removed from its location on a rail without necessitating the removal of bolts, clamps or other 35 clamping means and the device is further adapted to be relocated by simply placing the derailing support on a cross tie member in engagement with the rail and placing the 40 derailing member on the rail all in a manner as will be hereinafter described.

In the accompanying drawings constituting a part hereof and in which like reference characters designate like parts, Fig. 45 1 is a plan view in elevation of a derailing device embodying the principles of this invention; and Fig. 2 a side elevational view thereof.

Referring to the figures of the drawings 50 the structure therein illustrated comprises a base or support 1 of substantially rectangular shape having a projecting portion 2 extending underneath the rail flange 3, Fig.

2. The projecting portion is provided with a hooked end 4 which engages the outer 55 flange of the rail as shown. The base member 1 is provided with a depending flange member 5 of any suitable length which is adapted to engage the side of a cross tie support 6 on which the rail is secured. The 60 base is further provided with a pair of pedestal journal members 7 having a recessed or counterbored portion 8 formed in inwardly projecting lugs 9 and having openings 10 65 therein adapted to receive a pin 11.

A derailing member 12 having a vertically flanged portion 13, and a lip 14 that constitutes a track for the wheel flange is pivoted to the support 1 at 11. The member 12 is generally formed underneath to a shape 70 complementary to the form of rail with which it is adapted to be engaged. The derailing member 12 is provided with a web portion 15 having a cylindrically shaped lug 16 adapted to fit into the counterbore 8 of 75 the base and being further provided with an opening centrally of the body portion 16 through which the pin 11 is adapted to pass to pivotally join the derailing member 12 with the supporting base member 1. 80

The derailing member is provided with a depending flange portion 17, Fig. 2, adapted to engage the ball or side of the rail which functions to cooperate with the hook 4 and flange 5 of the base to interlock the derailing device with the rail and cross tie. 85

The device is assembled by disposing the base 1, with the derailing portion 13 laid back on its support, underneath the flange of the rail as shown in Fig. 2 with its depending flange 5 in juxtaposition with the cross tie 6. The base 1 is pulled back against the flange of the rail and placed against the side of the tie to be in intimate contact with the rail and tie and in this position the derailing member 12 is thrown forward on its hinge to engage the rail in the manner shown in Fig. 2. In this position the flange 17 intimately engages the ball of the rail and prevents the derailing member from 90 being displaced by the force of a wheel passing over it. The derailing member is otherwise locked against movement by the hooked end 4 of the projecting portion 2 of the base and the flange member 5 so that when the 100 device is assembled in its operative position 105

it is fixed against movement without the need of clamping means. A pin 20 may be placed in suitable openings provided in the pedestal 7 and the web 15 to lock the derailer 5 in its operative position on the rail.

When it is desired to locate the derailing member in any position for an indefinite period of time, it may be desirable to secure it against theft and for this purpose an opening 18 is provided in the base for receiving a spike which may be driven in the cross tie 6. The fastening means is obviously not necessary to make the device suitable for use in the manner hereinbefore described which is 15 obvious from the foregoing description of the structure and its function.

It will be evident from the foregoing description of this invention that derailing devices made in accordance therewith provide 20 simple means for accomplishing the derailing of railway vehicles. It is further evident that the device may be mounted in its operative position and is capable of resisting the forces acting upon it in its derailing function without necessitating the use of clamping members as in the prior art structures. It 25 is further evident that changes may be made in the design and arrangement of the several cooperating parts without departing from 30 the principles of this invention.

We claim:

1. A portable device for derailing railway vehicles comprising in combination a base member and a derailing member, said derailing member being pivotally joined to said 35 base member, and said base and derailing members being adapted to cooperatively engage a rail and cross tie to securely hold

said derailing member in its operative position. 40

2. A portable device for derailing railway vehicles comprising in combination a base member and a derailing member, said derailing member being pivotally joined to said base member, and said base and derailing members being provided with means adapted 45 to cooperatively engage a rail and cross tie to securely hold the device in its operative position.

3. A portable device for derailing railway vehicles comprising in combination a base member and a derailing member, said derailing member being pivotally joined to said base member, said base member having rail and cross tie engaging portions and the derailing member having a rail engaging portion by means of which said members cooperate to securely hold the device in its operative position. 50

4. A portable device for derailing railway vehicles comprising in combination a base member and a derailing member, said derailing member being pivotally joined to said base member, said base member having an extending portion provided with a hooked 55 end projecting underneath the rail and engaging the rail flange, said base being further provided with a tie engaging portion, and said derailing member having a flange for engaging the ball or head of the 60 rail. 65

In testimony whereof, we hereunto sign our names.

GEORGE H. FRAZIER.
ALBERT E. HERROLD.
